(57) CLAIM

The ornamental design for a cutting board, as shown and described.

DESCRIPTION

FIG. 1 is a perspective view of a cutting board showing our new design;

FIG. 2 is a front elevation view thereof;

FIG. 3 is a right side elevation view thereof, the left side being a mirror image of the right;

FIG. 4 is a top plan view thereof;

FIG. 5 is a bottom plan view thereof;

FIG. 6 is an enlarged alternate right side view thereof; and, FIG. 7 is an alternate perspective view thereof.

The accompanying drawings include broken lines that form no part of the claimed design.
